UNITED STATES PATENT OFFICE.

WILLIAM F. SNOHR, OF CHICAGO, ILLINOIS.

TELESCOPING GATE.

1,115,605.

Specification of Letters Patent.

Patented Nov. 3, 1914.

Application filed May 22, 1911. Serial No. 623,698.

To all whom it may concern:

Be it known that I, WILLIAM F. SNOHR, a citizen of the United States, residing at Chicago, in the county of Cook and State 5 of Illinois, have invented certain new and useful Improvements in Telescoping Gates, of which the following is a description, reference being had to the accompanying drawings, forming a part of this specification, in which corresponding numerals of 10 reference in the different figures indicate like parts.

The primary object of my invention is to provide simple, durable and effective safety 15 gates adapted to be actuated by fluid pressure for use upon street and interurban cars, the aim being to enable the opening and closing of said gates to be entirely under the control of a conductor or other authorized person so that passengers may be prevented from passing said gates except as 20 they may be caused to open by the one in charge thereof.

Other objects are to enable air from the 25 ordinary brake-cylinder reservoir to be employed for actuating the gates or barriers at alternately low and high pressures according as they are closed or opened, to alternately lock said barriers closed by the 30 direct action of the compressed fluid, to unlock them thereby for retraction, to provide means whereby a single pressure regulator may be utilized in connection with gates at opposite ends of a car so that those at the 35 front end may be held constantly retracted while the others are being opened and closed.

To these and other subsidiary ends, my invention consists in the combination of elements hereinafter more particularly described and definitely pointed out in the 40 claims.

In the drawings, Figure 1, is a vertical sectional view of the corner-post of an ordinary street-car showing my improved automatic safety gate connected therewith with the bars withdrawn, the cylinders inclosing the sliding bars being shown in longitudinal section as are also the cylinders of the automatic locking devices, one of said 50 bars being also sectioned to show the coiled spring therein, the cylinders being connected with pipes leading to a source of compressed air. Fig. 2, is a like view showing the gate bars extended. Fig. 3, is an 55 enlarged sectional view taken upon the line 3, Fig. 2, viewed in the direction of the ar-

row there shown. Fig. 4, is a diagrammatic view showing two gates as they would be disposed at opposite ends of a car, together with a source of compressed air, and intermediate pipe connections and valves, the rear of the car being assumed to be at the left hand. Fig. 5 is an enlarged sectional view of a special form of controlling valve showing the parts in position to control the 60 air for holding the gate open at the forward end of the car. Fig. 6, is a like view of a companion valve, showing the ways adjusted for causing an extension of the gate bars at the rear end of the car. Fig. 7, is an enlarged view, partly in section of the reducing valve. Fig. 8, is an elevation of a portion of the rear end of a street car showing the gate extended.

Referring to the drawings, 1, Figs. 1, 2 and 4, represents the corner-post at the forward end of a street car upon the left-hand side of the platform. In the example illustrated, the car to which the invention is applied is of the "pay-as-you-enter" type 75 and the aim is to provide a safety-gate for both front and rear, so that they may be used alternately as the condition of service may require. Extended through said post are tubes or cylinders 2, which are arranged 80 horizontally and extended lengthwise of the car so as to be hidden in the wall thereof. Each of said tubes is threaded at the end which projects through the post and is provided with collar nuts 3 and 4, by means of 85 which it is held rigidly in place. A screw cap 5, is attached to the inner end of each of said tubes and into said cap is tapped a short tube 6, which is connected by an elbow joint with a pipe 7, which is thereby placed 90 in communication with each of the tubes 2. The pipe 7 is connected by means of a T-coupling 8, Figs. 1 and 2, with a pipe 9, which, as illustrated in Fig. 4, is bent upwardly, laterally, downwardly and thence 100 laterally, to connect with a pipe 10, corresponding to the pipe 7, and in communication with tubes or cylinders 11 at the rear end of the car, which cylinders are secured to a corner-post 12, said tubes being counterparts of the tubes 2. A pipe 13 is connected to the pipe 9 at 14. Interposed in the pipe 13 is a reduction valve generally designated by 15, an enlarged view of which is shown in Fig. 7. Said valve is of a well 105 known construction, having a casing 16, the chamber in which is divided by a partition

17, arranged to form a valve-seat, the opening in which is adapted to be closed by a valve 18, upon a tubular valve-stem 19, having an opening 20 therein. Said stem is 5 extended through the usual stuffing box into a casing 21, having a diaphragm 22 therein connected with the stem. A spring 23, serves to hold said valve normally open. A by-pass 24 is connected with the pipe 13 upon opposite sides of said reduction valve, 10 in which by-pass there is inserted an ordinary globe-valve 25, which is held normally closed by means of a spring 26, Fig. 7. The pipe 13 is connected at 27 with a pipe 28, having three-way valves 29 and 30 connected therewith, enlarged views of which are shown in Figs. 5 and 6. The details of 15 said valves will be described later. A bent pipe 31, has one end connected with the valve 29 and the other with the valve 30. A pipe 32, serves to connect the pipe 31 with a tank 33, which serves as a source of compressed air and in practice, would be the ordinary compressed air-tank connected 20 with the brake operating mechanism.

Connecting the cylinders 2, is a pipe 34, which is connected with the valve 29, by means of a pipe 35. A pipe 36, in like manner connects the tubes 11, at the rear end of 30 the car, as shown in Fig. 4, and is in turn, connected with the valve 30 by means of a pipe 37. A cylinder 38, is secured to each of the cylinders 2, by means of a headed screw 39, Figs. 1 and 2, which is tapped into 35 the cylinder as shown. Each of said screws is centrally bored for the reception of a bolt 40, one end of which is attached to a piston 41, fitted within said cylinder. The bolt is adapted to enter the cylinder 2, as shown in Fig. 2, for the purpose hereinafter stated 40 but it may be retracted to the position shown in Fig. 1, by the action, presently to be described, of compressed air upon the piston, supplemented by the action of a spring 42; 45 the sole purpose of which is to hold said piston in said position when there is no air pressure in the main tank. The pipe 34 is connected near its ends with the cylinders 38, by short pipes 43. Communication is 50 also established between the cylinders 2 and the outer ends of the cylinders 38, by means of pipes 44 and 45, connected by the usual fittings 46, 47 and 48. The cylinders 11 are connected with cylinders 49, which are 55 counterparts of the cylinder 38, and are provided with the several pipe connections and other coacting elements above described and for a like purpose.

The valves 29 and 30, the former of which 60 is located at the front and the latter at the rear of the car, are identical in construction and are intended to control the admission of compressed air at either high or low pressure as may be desired to the cylinders 2, 65 and 11 respectively. Each valve is provided

with a cylindrical casing having four outlets,—three for the service pipes, referred to and an exhaust opening 50. The plug 51 is provided with two passages 52 and 53, corresponding to those of the usual two-way valve and also an L-shaped passage 54, the limbs of which are arranged to extend from the center to the circumference of the plug at right angles to each other, one of said limbs in the valve 29 being located midway 75 between the outlets of the two passages 52, 53 and the other between the outlets of the passage 52, while in the valve 30 the arrangement is reversed by placing the outlet of one of said limbs between the outlets of 80 the passage 53. When the handle 55, Fig. 4, of the valve 29 is set as shown, the passages 52 and 53 are closed as indicated in Fig. 5, and the passage 54 is in communication with pipes 31 and 35, thereby permitting air 85 under high pressure to pass from the tank 33 to the pipe 35 and thence into the cylinders 38 to act upon the pistons 41 and move them into the respective positions shown in Fig. 1.

As above stated, the passages 54 in the valves 29 and 30 are oppositely located with respect to each other, one being upon the right-hand and the other upon the left-hand side of the plug. When, therefore, the handle 55 of the valve 30 is disposed as shown in Fig. 4, the respective positions of the passages 52, 53 and 54, will be as shown in Fig. 6. When thus disposed, the passage 52 will serve to connect the pipes 31 and 28, 100 the passage 53 will connect the pipe 37 with the exhaust port 50 and the passage 54 will be closed. With such a disposal, the air is free to escape from the pipe 37, while that from the tank is free to pass through the 105 pipes 32 and 31, valve 30, pipes 28 and 13 to the reduction valve 15. The valve plug 18 is held normally open by the spring 23, thereby permitting the air to pass into the upper chamber of the valve and thence 110 through the opening 20 and hollow-valve-stem 19, to the chamber above the diaphragm 22, the downward pressure upon which causes the valve to close at a predetermined pressure. In the meantime the 115 air, at the reduced pressure determined by the valve, will have passed into the pipes 7, 9, and 10 respectively and thence into the ends of the cylinders 2 and 11.

Within the cylinders 2 are fitted tubular 120 gate-bars 56, and within the cylinders 11 are placed like bars 57. The gate bars are smaller in diameter than the cylinders in which they are inclosed, said bars being provided with rings or collars 58, 59, Figs. 1 125 and 2, upon the inner ends, with an annular groove 60 between them of a width adapted to receive the bolt or part 40, as hereinafter described. The rings 59 are intended to serve as pistons for the purpose hereinafter 130

stated. In the forward ends of the cylinders are placed sleeves 61, which serve as sliding bearings for the bars 56. Said sleeves are provided with longitudinal grooves 62 as more clearly shown in Fig. 3, for the purpose hereinafter stated. Upon the outer ends of the bars 56 are formed heads 63, which are adapted to fit within sockets against the ends of the sleeves 61, when the bars are positioned as shown in Fig. 1, so as to close the openings or grooves 62.

Coiled springs 64, are preferably placed within the bars 56, said springs having one end connected to a pin 65, Fig. 1, and the other to a pin 66 in the cap 5. One purpose of the springs is to hold the gate-bars in place within the tubes when there is no air-pressure in the tank, and another is to prevent the bars from being pushed outwardly with excessive force when air pressure is exerted behind them. Like springs, not shown, are arranged in the same manner within the bars 57.

The speed of movement of the gate-bars may also be controlled by means of nozzles 50^a, Figs. 4, 5 and 6, having restricted openings 50^b, the area of which may be varied by means of adjusting screws 50^c, thereby enabling the escape of air to be so controlled as to insure any desired speed in the movement of the gates. This feature enables the springs 64, to be dispensed with; but inasmuch as they serve to hold the bars within the tubes when there is no air pressure in the tank 33, I prefer to retain them.

Should the valve 15, fail to operate so as to release the air from the rear of the gate cylinders, the retraction of the gates when air at high pressure is admitted in front, would result in causing an increase of pressure therein, which would tend to defeat the desired action. As a precautionary measure I have, therefore, interposed a pop-valve 9^a in the pipe 9 adapted to open and permit the escape of air when it equals or exceeds a pressure sufficient to operate the reduction valve.

The operation of said device is as follows: Assuming the rear or left-hand end of the car, as shown in Fig. 4, to be used for the ingress and egress of passengers and that while so used it is desirable to withdraw the gate-bars at the opposite end, the valves 29 and 30 which are located respectively within easy access of the conductor at opposite ends of the car, are set respectively in the positions indicated in Figs. 4, 5 and 6, and the operating handle removed from the valve 29. The air from the tank at maximum pressure is thus permitted to pass directly through the passage 54 in the valve 29, through the pipes 35, 34 and 43, into the cylinders 2 against the pistons 41, thereby moving them outwardly and withdrawing

the bolts 40 from the tubes 2. At the same time air is admitted to the cylinders 2, through the ends of the pipe 34, thereby pressing against the piston, or rings 59 and forcing the gate-bars back into the cylinders to the full limit, as shown in Figs. 1 and 4. Simultaneously the air from the tank passes through the passage 52 in the valve 30 and thence, as described, through the reduction valve and, at a reduced pressure, into the pipes 7, 9 and 10, where it presses against the inner ends of both sets of bars, thereby tending to force them out. The high pressure from an opposite direction against the shoulders of the rings 59, 80 Figs. 1 and 2, however, is more than sufficient to overcome said outward pressure and the bars 56, at the front of the car are thereby held within the cylinders as shown in Figs. 1 and 4. Reference to Fig. 6 will show that when the valve handle 30 is moved to the position shown in Fig. 4, so as to permit air to pass through the passage 52, to the reduction-valve, the passage 54 is closed and the passage 53 is in communication 90 with the pipe 37 and the discharge port 50, thereby permitting the high pressure air to escape from the side of the pistons not shown, within the cylinders 49, next to the cylinders 11, which correspond to the pistons 41, 95 thereby unlocking the bolts controlled by said pistons, when the low pressure air within said cylinders, having first forced the gate-bars 57, outwardly to the full limit, will pass through the pipes 44 upon the opposite side of the pistons 41, as shown in Fig. 2, and force the bolts 40, against the action of the springs 42 into the grooves 60, thereby positively locking said bars 57 in an extended position as shown in Fig. 4. 100 In order to retract the gate-bars 57, the handle 55, of the valve 30, is moved to the extreme right as indicated in dotted lines in Fig. 4. This movement causes the duct 52, of said valve to be brought into communication with the pipe 28, and exhaust port 50, and the duct 53, to communicate with the pipes 31 and 37, while the duct 54, is closed. This adjustment permits the low pressure to escape from behind the pistons 115 in the cylinders 11 and 49, at the same instant that the high pressure air is admitted to the opposite ends of said cylinders; said high pressure air first serving to retract the locking-bolts in the cylinder 49, and then to retract the bars 57, by pressing against the front of the piston-rings at the rear ends of said bars.

It is obvious that when the handle of the valve 30 is turned to the extreme right at the angle indicated by the dotted lines in Fig. 4, the passage 52 will be in communication with the pipe 28 and the escape port 50; but, assuming the valve 15 to have been previously closed in the manner described, such closure 125 130

would prevent the escape of low pressure air from the cylinders. In order to overcome this difficulty, I have provided the by-pass 24 and valve 25, which is normally closed, 5 but is caused to open against the action of the light spring 26 when the pressure is removed from the left hand side, thereby permitting the air pressure from the right hand side to lift it. The pressure being thus reduced in the chamber above the valve 18, the 10 air is permitted to escape from the diaphragm chamber when the spring 23 acts to open the valve 18.

The gate-bars are of such a length that 15 when extended as shown in Fig. 8, they will project within a short distance of the vertical post 67, to which is connected the usual railing within which the conductor stands upon the cars of this type. The passengers 20 enter the cars at the left of said post and pass through a door adjacent to the railing. Upon leaving the car, however, they pass through a door communicating with the 25 railed space at the right of the post 67. The gate-bars, however, being normally extended across the passage, the passenger cannot alight until they are withdrawn at the instance of the conductor who moves the 30 valve handle 55, for that purpose after the car is stopped, thereby avoiding accident. Until the valve is properly manipulated, the 35 gate-bars at the rear of the car are locked outwardly by means of the lock-bolts 40 which are held in engagement with the grooves 60 as a result of the air pressure upon the pistons 41 as shown in Fig. 2. When the valve is reversed the gate-bars are 40 withdrawn and in order to prevent the heads 63 or any part of said bars from being 45 engaged or entangled with the clothing of a passenger, the grooves 62 in the sleeves 61, are provided, which permits an escape of air therefrom which would act to blow any article of clothing from the sockets 50 into which the heads are adapted to enter. When the bars are withdrawn the outlet 55 grooves are closed by said heads in the manner shown in Fig. 1. By limiting the outward movement of the bars so as to hold 60 them away from the post 67, all danger of injury to the hand of one grasping said post may be avoided.

I do not wish to be limited to the exact construction shown nor to any particular 55 number of bars to obstruct a given passage. While I prefer to employ two as shown, it is obvious that one may be omitted without departing from the spirit of the invention, and in many cases one would serve the purpose satisfactorily.

From what has been stated, it will be obvious 65 that the apparatus described constitutes a complete coacting system for controlling the barriers at opposite ends of a car so as to enable high and low pressure

air to be alternately used at one end of the car to actuate the gate-bars, while those at the other end are held stationary; which result is rendered possible by means of the 70 ducts 54, in the front and rear valves, the one at the front being in constant use, while that at the rear is constantly closed, a single reduction-valve, common to both sets of gate-cylinders, and a source of high pressure air in communication with the pipes 75 leading to said gate-cylinders, in which three-way valves are located.

Having thus described my invention, I claim:—

1. A gate system for controlling different 80 passage-ways, in which is combined a cylinder located at each passage-way, a telescoping gate-bar fitted therein, a piston upon each bar, a controlling valve arbitrarily located with respect to each passage-way, a 85 source of compressed air in communication with each of said controlling valves, a separate conduit leading from each valve to the forward end of the cylinder which said valve is intended to control, a conduit for connecting each of said valves to the rear end of each of said cylinders and a reduction-valve interposed in said conduit, each of said controlling valves being provided with complementary ways for simultaneously admitting 90 air through said reduction-valve to the rear of both of said cylinders while releasing high pressure from the front of one of them and vice versa and a way for admitting high pressure air to the front of said cylinder 95 while closing both of the other ways, whereby one of said gates may be held retracted while the other is being operated.

2. A gate system for controlling different 100 passage-ways, in which is combined a cylinder located at each passage-way for the reception of a slidable gate-bar to guard 105 said passage-way, a slidable gate-bar fitted in each of said cylinders, a piston secured to each of said bars, a three-way valve arbitrarily located with respect to each passage-way, a source of compressed air, a conduit leading therefrom to each of said three-way valves, a reduction-valve, a conduit leading 110 from each of said three-way valves to said reduction-valve, a conduit leading from said reduction-valve to the rear end of each of said cylinders to permit air at a low pressure to be admitted thereto to press outwardly against each of said pistons, and a 115 conduit leading from each of said three-way valves to the forward end of one of said cylinders for admitting air thereto at a high pressure to cause the gate-bar at one passage-way to be operated regardless of the 120 relative position of that at another.

3. In a gate system for guarding a plurality of passage-ways, the combination of a cylinder adjacent to each passage-way for the reception of a slidable gate-bar, a slid- 125

able gate-bar fitted in each of said cylinders, a piston secured to each of said bars, a three-way valve located in operative proximity to each of said passage-ways, a source 5 of compressed air in communication with each of said valves, a reduction-valve, a conduit leading from each of said three-way valves to said reduction-valve and from said reduction-valve to the rear of each of said 10 cylinders to permit air at low pressure to enter at the rear thereof, a by-pass connected with said conduit upon opposite sides of said reduction-valve, an escape valve in said by-pass for allowing an escape of air from 15 said cylinders when pressure is released from behind said escape-valve, and a conduit leading from each of said three-way valves to the forward end of the cylinders at the passage-way which a given valve is 20 intended to control, to permit air at high pressure to enter said cylinder for retracting said gate-bars.

4. A gate system for guarding a plurality of passage-ways, comprising a gate located 25 at each passage-way, each gate consisting of a cylinder, a gate-bar arranged to telescope therewith and a piston, in combination with a controlling valve for each gate, a source of compressed air in communication 30 with each of said controlling-valves, a conduit for connecting said controlling-valves with the inner ends of each of said cylinders, a reduction-valve located in said last named conduit for reducing the pressure 35 of air which may be admitted to said cylinders, a conduit for connecting the forward end of each cylinder with the controlling-valve intended to control the gate of which that cylinder forms a part, each 40 controlling-valve having three ways, two of which when in a given position act simultaneously, the third being closed, one of said two to admit air to the inner end of each of said cylinders while the other permits its escape 45 from the front of one cylinder connected therewith, and when reversed said one permitting a release of air from the rear of said cylinders while admitting it in front of said one, said third way serving when 50 open and the other two are closed, to admit air directly from said source to the front of said cylinder.

5. The combination in a gate of a cylinder, a telescoping gate-bar fitted therein, a piston upon said bar at a predetermined distance from its forward end, a source of compressed air, means for admitting the same behind said piston, means for releasing 55 said air, means for locking said gate-bar in an extended position and air-controlled means for actuating said locking means when said gate-bar is fully extended.

6. The combination in a gate of a cylinder, a telescoping gate-bar fitted therein, a 60 piston upon said bar at a predetermined

distance from its forward end, a source of compressed air, means for admitting the same behind said piston to project the same, air-controlled means for locking said gate-bar in an extended position, means for admitting air in front of said piston to retract 70 said bar and air-controlled means for normally holding said locking means in an unlocked position during the presence of said air in front.

7. The combination in a gate, of a cylinder, a telescoping gate-bar fitted therein, a piston upon said bar at a predetermined distance from its forward end, a source of compressed air, means for admitting the same behind said piston, means for releasing 80 said air, means for locking said gate-bar in an extended position, air-controlled means for actuating said locking means when said gate-bar is fully extended, 85 means for normally holding said locking means in an unlocked position and means for returning and holding said bar within the cylinders when the air is released from behind the piston.

8. The combination in a gate of a cylinder, a telescoping gate-bar fitted therein, a source of compressed air in communication with the rear end of said cylinder and a coiled spring having one end connected to a stationary point and the other to said bar to cushion and control the outward movement of the latter when air is admitted to said cylinder behind said bar.

9. The combination in a gate of a cylinder, a telescoping gate-bar fitted therein to be projected from one end, a source of compressed air in communication with the rear end of said cylinder, a coiled spring having one end connected to a stationary point and the other to said bar, air-controlled locking means for locking said bar in position when projected, and means for releasing said locking means when the air pressure is released from behind said bar.

10. The combination in a gate of a cylinder, a telescoping gate-bar fitted therein, a piston upon said gate-bar at a predetermined distance from its forward end, a source of compressed air, valve controlled means for admitting the same behind said piston to project said bar, valve controlled means for releasing said air from behind said piston, means for admitting air under pressure in front thereof and openings adjacent to said bar at its forward end for permitting an outflow of air when the bar is returned to the cylinder to prevent a contact of clothing therewith.

11. The combination in a gate of a cylinder, a telescoping gate-bar fitted therein, a piston upon said gate-bar at a predetermined distance from its forward end, a source of compressed air, a secondary cylinder arranged at right angles to said gate-bar

cylinder, a piston therein having a locking bolt adapted to engage said gate-bar when the latter is projected, means for admitting air under pressure to the rear end of said gate-
5 bar, means for admitting air under pressure to the outer end of said secondary cylinder when said bar is fully extended to actuate the piston therein to lock said bolt, means for releasing air from behind said bar and
10 from said secondary cylinder and means for admitting air under pressure to the opposite end of said secondary cylinder to withdraw said bolt when air is released from behind said bar.
15 12. A gate-system for guarding separate passage-ways, in which is combined a gate located at each passage-way, each gate having a cylinder, a telescoping gate-bar, and a piston upon said gate bar at a predetermined distance from its forward end, a source of compressed air, two three-way valves each in communication therewith, a conduit leading from one side of one of said valves, to the forward end of one of
20 said cylinders, a conduit leading from the corresponding side of the other of said valves to the forward end of the other of

said cylinders, a conduit leading from the opposite sides of said valves to the rear ends of each of said cylinders, a reduction valve 30 interposed in said conduit and a by-pass leading around said reduction valve, said pass having a valve therein openable in a reverse direction from that of said reduction valve.

35 13. The combination in a gate of a cylinder, a telescoping gate-bar fitted therein, a piston upon said bar at a distance from its forward end corresponding substantially to the extent of its longitudinal movement, 40 means for alternately admitting air under pressure to opposite sides of said piston, means for alternately releasing air from opposite sides of said piston and means for permitting an escape of air around said bar from the forward end of said cylinder during the retracting movement of said bar.

45 In testimony whereof, I have signed this specification in the presence of two subscribing witnesses, this 18th day of April, 1911.

50 WILLIAM F. SNOHR.
